(57) **CLAIM**

The ornamental design for a motorcycle grip, as shown and described.

DESCRIPTION

FIG. 1 is a perspective view of the motorcycle grip of the present invention.

FIG. 2 is a first side elevation view thereof.

FIG. 3 is a second side elevation view thereof.

FIG. 4 is a third side elevation view thereof, which is opposite the first side elevation view of FIG. 2.

FIG. 5 is a fourth side elevation view thereof, which is opposite the second side elevation view of FIG. 3.

FIG. 6 is an end view of the visible end thereof; and,

FIG. 7 is an end view of the opposite end thereof.

Those portions of the motorcycle grip shown in broken lines are included for illustrative purposes only and form no part of the claimed design.
